UNITED STATES PATENT OFFICE.

MAXWELL S. HART, OF NEW BRITAIN, CONNECTICUT.

LOCKER.

Application filed January 10, 1924. Serial No. 685,299.

To all whom it may concern:

Be it known that I, MAXWELL S. HART, a citizen of the United States, and a resident of New Britain, county of Hartford, 5 and State of Connecticut, have invented certain new and useful Improvements in Lockers, of which the following is a specification.

This invention relates to clothing lockers, 10 and more particularly to what may be termed a duplex locker unit for individual use, each unit including two separate sets of compartments, each set comprising a hat compartment and a coat compartment all 15 arranged so as to occupy the minimum amount of floor space and at the same time having sufficient space for the proper storage of clothing.

One object of this invention is to provide 20 a locker unit of the above nature in which both compartments of a set may be locked by a locking means in common thereto and independent of the locking means for the other set.

25 A further object of this invention is to provide a device of the above nature in which both doors of the hat and coat compartments belonging to one individual may be if desired, simultaneously locked by the 30 operation of a single locking mechanism.

A further object is to provide a locker 35 unit having a pair of relatively narrow coat compartments arranged side by side and associated with a pair of relatively wide hat compartments.

40 A further object is to provide a duplex locker unit having both hat compartments arranged directly above a pair of coat compartments so that all of the compartments 45 will be in the most convenient and accessible positions.

45 A further object is to provide a locker unit of the individual type having the minimum number of key-operated locking devices.

50 A still further object is to provide a locker of the above nature which will be simple, inexpensive to manufacture, compact in size, and very efficient and durable in use.

55 With these and other objects in view, there have been illustrated in the accompanying drawings, two forms in which the invention may be conveniently embodied in practice.

Fig. 1 is a perspective view of the pre-

ferred form of locker unit, shown with the doors in closed position.

Fig. 2 is a fragmentary rear view of the front wall of the locker unit, showing the construction of the door locking mechanism. 60

Fig. 3 is a fragmentary sectional view of the front portion of the upper hat compartment taken along the line 3—3 of Fig. 2, looking in the direction of the arrows.

Fig. 4 is a fragmentary rear view of the 65 door of the left-hand coat compartment and the slideable locking bar co-operating therewith, said parts being shown in separated relation.

The former type of individual clothing 70 locker for use in clubs, factories, schools, etc., was usually rectangular in shape and had a shelf at the top, upon which the hat, lunch box, etc., of the individual were to be placed. The compartment below the 75 shelf was used to receive his coat and other garments. Owing to the fact that a hanging coat or other garment generally occupies considerably less width of the locker than the user's hat, lunch box, etc., it resulted that only a portion of the space in the coat compartment was utilized. 80

Attempts have been made to economize 85 space in such locker systems by employing two separate sets of lockers, the lockers of one set being long and narrow to receive coats, and the lockers of the other set being short and wide to receive hats, lunch boxes, etc. Such systems were subject to the disadvantage that the two lockers for any one 90 individual were often located far away from each other, making it inconvenient to use them simultaneously. A further disadvantage was that the user was required to operate two different locks to open the 95 lockers.

By means of the present invention, the 100 above and other disadvantages have been entirely avoided. This has been accomplished by providing a locker unit having two long and narrow vertical coat compartments and two short and wide horizontal hat compartments arranged directly above the coat compartments, each of said compartments having its own separate door. 105 Independent locking means for each set is provided within the space above the coat compartments and below the hat compartments. In the particular form shown herein, the locking means for each set of doors 110

is carried by the body of the locker instead of by the doors. Also, in this form, the locking means for each set of doors is such that either door of a set may be unlatched 5 without unlatching the other door.

Referring now to the drawings in which like reference numerals denote corresponding parts throughout the several views, the preferred embodiment of locker unit herein 10 illustrated, comprises side walls 10 and 11, front and rear walls 12 and 13, and top and bottom walls 14 and 15. In the particular form shown, the space inside the locker is divided into five compartments by means 15 of three horizontal partitions 16, 17, and 18 located near the top of the locker, and a vertical partition 19 located in the lower part of the locker, as clearly shown in Fig. 1. The two horizontal upper compartments 20 between the top wall 14 and the partition 17 extend the full width of the locker and are designed to be used for receiving hats, lunch boxes, etc. These compartments will be hereinafter designated as the hat compartments. 25 The relatively long and narrow compartments formed in the lower part of the locker and separated by the vertical partition 19 will be hereinafter designated as the coat compartments.

30 It will be understood that if desired, the lower horizontal partition 18 may be omitted, in which case the entire space below the partition 17 may be utilized for the separated coat compartments.

35 The right-hand coat compartment and the upper hat compartment of the locker unit are adapted to be privately used as a set by one individual, while the left-hand coat compartment and the lower hat compartment are adapted to be privately used as a 40 set by a second individual, thereby accommodating two individuals in the one unit described. It is within the spirit of the invention to reverse the above arrangement, 45 in which case one individual will use the right-hand coat compartment and the lower hat compartment, while the second individual will use the left-hand coat compartment and the upper hat compartment.

50 The hat compartment at the top of the locker unit is provided with a door 20 adapted to swing about a vertical axis on hinges 21 at the left-hand side of the locker frame, said door having a handle or knob 22, by means of which it may be moved to open or closed position. The lower hat compartment is provided with a similar door 23, but in this instance, the door is adapted to swing out in the opposite direction on hinges 55 24 located at the opposite side of the locker frame. The coat compartments are adapted to be closed by a pair of doors 26 and 27 hinged to the front adjacent the edge of the vertical partition 19. By this novel 60 hinge arrangement for the several doors, the

problem of providing effective and yet simple locking means for each set of doors is greatly facilitated and simplified.

Each of the doors 20, 23, 26, and 27 is provided on its inner edge with an elongated 70 Z-shaped locking flange 28 preferably welded in place. The outer leg 29 of each Z-shaped flange is parallel to the plane of its associated door and has a cut-out section 29^a near the top thereof. The lower part of 75 each cut-out section is provided with an inwardly bent cam projection 30, for a purpose to be hereinafter specified.

Each of the hat and coat compartment doors is adapted to be latched by means of 80 vertical sliding bars 31, 32, 33, and 34 respectively. The locking bars 31 and 32, together with a co-acting locking bolt 56, hereinafter described, constitute the locking means for one set of compartment doors, 85 and these bars are located on the right-hand side of the locker frame adjacent the free edges of the doors controlled thereby. The locking bars 33 and 34, together with a co-acting bolt 55, hereinafter described, constitute the locking means for the other set of compartment doors, these bars being located on the left-hand side of the locker frame. The inwardly projecting sides of the several locking bars 31, 32, 33, and 34 90 are provided near their upper ends with cut-out portions 35, 36, 37, and 38, respectively.

In order to latch the doors in closed position, each of the aforesaid bars is provided with a horizontally-extending lug 39, 40, 41, and 42 respectively, which may be secured thereto in any suitable way, as by welding. These lugs respectively project through the cut-out portions 35, 36, 37, and 100 38, and are adapted to lie behind the cam projections 30 of the Z-shaped flanges 28 when the doors are closed. By the unique arrangement of hinging the aforesaid doors, both doors of one set open from one edge 105 of the locker frame, while both doors of the other set open from the opposite edge of the locker frame. This makes it possible to provide the respective locking or latching bars for each set in vertical alinement at one side 110 of the frame, so that they may both be controlled by a single co-acting locking bolt, and so that they will both stand in an out-of-the-way position, in no way interfering with free access to the interior of each compartment.

In the operation of closing the doors, the cam projections 30 on the doors will force the lugs 39, 40, 41, and 42 upwardly, causing said lugs to ride up over the cam projections 30 and to drop by gravity into the spaces behind said projections. The upper portions of the upper bars 31 and 33, and the lower portions of the lower bars 32 and 34 are provided with vertical slots 43, 44, 120 130

45, and 46 respectively, which are adapted to fit over stationary guiding pins on the front frame 12 of the locker. The other ends of said sliding bars are provided with 5 handle members 47 and 48, which are adapted to extend through vertical slots 49 and 50 in the front plate. The handle members 47 and 48 on each side of the locker are preferably located adjacent each other so that 10 they may both be grasped by one hand of the operator, leaving his other hand free to open the doors.

In order to dead-lock the two sets of latching bars in the positions shown in Fig. 2, 15 two independent key-operated locking devices 51 and 52 are provided within the space between the partitions 17 and 18, said devices being secured to the front wall 12 of the locker in approximate alinement with 20 the Z-shaped locking flanges 28. The locking devices 51 and 52 are provided with key receiving members 53 and 54 respectively, extending through the front wall 12 so as to 25 be readily manipulated by persons using the lockers. The locking devices 51 and 52 are provided with horizontal slideable dead-locking bolts 55 and 56 respectively, which are adapted to be moved into cut-out portions 57 and 58 on the inner flanges of the upper 30 sliding bars 31 and 33 to hold the same from being moved to release the upper doors. The dead-locking bolts will then be directly 35 above the tops of the lower sliding bars 32 and 34, and will prevent said bars from upward movement. When the parts are in this position, the doors will be positively locked securely in place.

In order to prevent the upper end of the lower sliding bars 32 and 34 from interfering 40 with the lower end of the upper sliding bars 31 and 33, the inner flanges of the bars 32 and 34 are cut down at 59 for a short distance and the front sides which engage the flat front wall of the locker are off-set 45 rearwardly so as to lie behind the lower ends of the upper bar 31 and 33. It will thus be seen that the locking devices 51 and 52 will serve to dead-lock both sets of doors 20, 27 and 23, 26 respectively. It will be evident 50 that the upper sliding bar 31 on the right-hand side of the locker must be made considerably longer than the bar 33 on account of the fact that its upper end must be opposite the Z-shaped flange 28 on the free edge 55 of the upper hat compartment door 20.

In operation, when an individual desires to place his hat and coat in the locker—as for example, in the lower hat compartment and the left-hand coat compartment—it will 60 merely be necessary for him to insert a key in the key-receiving member 53 and turn it in the proper direction to withdraw the dead-locking bolt 55 from the sliding bars 33 and 34. He will then grasp the knobs 65 47 and 48 on the left side of the locker and

will push them upwardly until the lugs 39 and 40 are above the cam projections 30 whereupon doors 23 and 27 may be opened by the use of the other hand of the operator. The knobs 47 and 48 will then be released 70 permitting the sliding bars 33 and 34 to drop by gravity to their original positions. In case it is desired to open only one of the doors, such as the coat compartment door 27, only the knob 48 will be raised to 75 permit said door to be opened.

By the term "common" as applied to the means for locking the doors of a set of compartments, it will be understood that such means includes any device in said set not individual to a particular compartment, whereby said compartment may be unlocked by the operation of a device external thereto. It also includes any means within the set of compartments whereby access is permitted 85 to two compartments by unlocking a single lock.

One important advantage of this invention lies in the fact that hats and other articles in the hat compartments can not possibly 90 be injured by drippings from umbrellas or rubber shoes located in the coat compartments, which injury was possible with certain lockers of this type wherein one of the hat compartments was situated underneath the coat compartments.

While there have been disclosed in this specification one form in which the invention may be embodied, it is to be understood that this form is shown for the purpose of 100 illustration only, and that the invention is not to be limited to the specific disclosure but may be modified and embodied in various other forms without departing from its spirit. In short, the invention includes all 105 the modifications and embodiments coming within the scope of the following claims.

Having thus fully described the invention, what is claimed as new, and for which it is desired to secure Letters Patent, is: 110

1. In a duplex locker unit, a pair of narrow coat compartments arranged vertically and side by side, a pair of wider hat compartments arranged horizontally above said coat compartments and one above the other, 115 individual doors for closing each of said compartments, and common means co-acting with one of said coat compartment doors and one of said hat compartment doors for locking the same.

2. In a duplex locker unit, a pair of narrow coat compartments arranged vertically and side by side, a pair of wider hat compartments arranged horizontally above said coat compartments and one above the other, 125 individual doors for closing each of said compartments, common means co-acting with one of said coat compartment doors and one of said hat compartment doors, and independent common means co-acting with 130

the other coat compartment door and the other hat compartment door for locking the same.

3. In a locker unit, two narrow coat compartments arranged vertically and side by side, two wider hat compartments arranged horizontally above said coat compartments and one above the other, separate doors for closing each of said compartments, and common means for locking one of said hat compartment doors and one of said coat compartment doors, said means comprising sliding latching bars adjacent the free edges of said doors, means on said doors for engaging said bars to hold the doors closed, and means for holding said bars from sliding, whereby said doors will be securely locked in closed position.
- 5
- 10
- 15

4. In a locker unit, two narrow coat compartments arranged vertically and side by side, two wider hat compartments arranged above said coat compartments and one above the other, separate doors for closing each of said compartments, and common means for locking one hat compartment door and one coat compartment door, said means comprising separate vertical latching bars, one adjacent the free edge of each door, means on each door for engaging its respective latching bar to hold the door closed, and deadlocking means for preventing said latching bars from sliding, whereby said doors will be locked in closed position.

35 5. In a locker unit, a pair of narrow vertical coat compartments arranged side by side, a pair of wide horizontal hat compartments arranged above said coat compartments and one above the other, separate doors for closing each of said compartments, each of said doors having a cam member adjacent its free edge, separate sliding bars for each door on the front of said locker unit adjacent said cam members, each of said bars having a latching lug adapted to be forced upwardly to clear its respective cam member and adapted to move down behind said cam member when said door is closed and means for independently operating each sliding bar.

50 6. In a locker, a frame comprising a plurality of sets of associated separate clothing compartments, each set comprising a relatively narrow coat compartment at the lower part of the frame and a relatively wider
55 hat compartment above the same and extending the full width of said frame and each set adapted to be used privately by a single individual, separate doors for closing each compartment, and separate locking
60 means common to each set for locking

the doors of said respective sets of compartments.

7. In a duplex clothing locker unit, a locker frame, an upright partition in said frame forming a pair of narrow coat compartments, doors hinged adjacent said upright partition for closing said coat compartments, a pair of spaced transverse partitions arranged within said frame above said coat compartments, said transverse partitions extending the full width of both coat compartments and forming a pair of wide hat compartments, one hat compartment door hinged to one side wall of said frame and the other hat compartment door hinged to the opposite side wall of said frame, and common means for locking one of said coat compartment doors and one of said hat compartment doors, said means being adjacent the free edges of said doors

8. In a duplex locker unit, an external locker frame and partitions therein forming a pair of narrow vertical compartments arranged side by side, and a pair of horizontal wide compartments arranged above said vertical compartments and one above the other and extending substantially the full width of both vertical compartments, the uppermost horizontal compartment and one of said vertical compartments comprising one individual set, and the lowermost horizontal compartment and the other vertical compartment comprising a second individual set, with doors for each compartment, and common locking means for each of said separate sets respectively. 90 95

9. In a duplex locker unit for a system of private clothing lockers, an external locker frame and partitions therein forming a pair of narrow vertical compartments arranged side by side, and a pair of horizontal compartments arranged above said vertical compartments and one above the other and extending substantially the full width of both vertical compartments, the uppermost horizontal compartment and one of said vertical compartments comprising one individual set, and the lowermost horizontal compartment and the other vertical compartment comprising a second individual set, with doors for each compartment, and common locking means for each of said separate sets respectively, each of said locking means including a common dead-locking device and independent latching devices for each door of the set. 100 105 110 115

In testimony whereof, I have affixed my signature to this specification.

MAXWELL S. HART
